UNITED STATES PATENT OFFICE.

LUTHER A. GAW, OF CHARLOTTESVILLE, VIRGINIA, ASSIGNOR TO DILLON-GAW MOTOR COMPANY, OF FAYETTEVILLE, WEST VIRGINIA, A CORPORATION OF WEST VIRGINIA.

SLEEVE-VALVE INTERNAL-COMBUSTION ENGINE.

Application filed August 11, 1926. Serial No. 128,651.

This invention relates to improvements in the sleeve valve type of internal combustion engine.

The primary object of this invention is 5 the provision of an improved cylinder casting block and head construction for most efficiently regulating the intake and exhaust of fuel and gas.

A further object of this invention is the 10 provision of an improved cam construction for operating sleeve valves.

A further object of this invention is the provision of improvements in sleeve valve operating mechanisms such as generically 15 set forth in my United States Patent #1,286,275, issued December 3, 1918, and my co-pending application, Serial No. 61,722, filed October 10, 1925; the present 20 application embodying improvements there-over in the simplification of the sleeve valve operating mechanism.

Other objects and advantages of this invention will be apparent during the course of the following detailed description.

In the accompanying drawings, forming a 25 part of this specification, and wherein similar reference characters designate corresponding parts throughout the several views,

Figure 1 is a longitudinal sectional view 30 taken thru a cylinder of the improved internal combustion engine, showing the sleeve valve, its operating mechanism, and the piston construction in the position which they 35 will assume with respect to the intake and exhaust ports at the start of the power stroke.

Figure 2 is a sectional view of the details 40 illustrated in Figure 1, but showing the parts arranged as they will appear as the exhaust is taking place.

Figure 3 is an enlarged sectional view of 45 the upper portion of an engine cylinder, showing the sleeve valve in position when the exhaust is fully open.

Figure 4 is a sectional view of details 50 taken at right angles to the view illustrated in Figure 3, substantially on the line 4—4 of Figure 3.

Figure 5 is a sectional view taken substantially on the line 5—5 of Figure 4.

Figure 6 is a sectional view taken substantially on the line 6—6 of Figure 2.

Figure 7 is a fragmentary view, partly in section, showing means upon which the cams 55 directly engage, for causing an operative movement of the sleeve valve.

Figures 8 and 9 are sectional views taken substantially on their respective lines in 60 Figure 1 of the drawings.

Figures 10 to 13 inclusive are views, partly diagrammatic, illustrating various positions of the cams during operation upon the means which operates the sleeve valve; Figure 10 showing the cams as they appear at 65 the start of the opening of the intake port; Figure 11 showing the positions of the cams as they appear as the intake about the starting to close and compression is about to start; Figure 12 showing the position of the 70 cams at the start of the power stroke; and Figure 13 showing the positions of the cams as the exhaust port is just starting to open.

Figure 14 is a fragmentary sectional view 75 showing the cylinder intake port with the adjacent intake port of the sleeve valve just starting to open.

In the drawings, wherein for the purpose of illustration is shown only a preferred embodiment of the improved sleeve valve 80 internal combustion engine, the letter A may generally designate the engine, which may include the cylinder block or casing construction B which includes a crank case C wherein a crank shaft D is rotatably mounted. A piston E operates in each of the cylinders of the engine, connected by a rod F to the crank shaft D in the usual manner. A sleeve valve G operates in each cylinder 85 between the piston and the cylinder walls, and the sleeve G is controlled by cam means H operating on means L which is connected with the sleeve valve. A detachable cylinder head construction M is provided for each cylinder of the engine A, and preferably only a single novel water hood or manifold P is provided for cooperation upon the cylinder block B and with the cylinder heads M to regulate the flow of the cooling 90 medium.

The cylinder block B is preferably provided with any approved number of cylin- 100

der chambers 15, each of which open directly on the top surface of the cylinder block B and on the upper openings of the cylinder chambers 15 detachable individual cylinder heads M are adapted to be positioned in a novel relation to be subsequently described. The cylinder block B is of course provided with a water jacket providing water compartments 17 surrounding each cylinder, and these water compartments have outlets 19 directly on the top surface of the cylinder block, so that the water may circulate about the cylinders thru the openings 19 into the water hood or manifold P and about the individual detachable cylinder heads M for cooling the latter, in the relation of parts to be more fully detailed hereinafter.

For each cylinder chamber 15 the block B is provided with an upper transverse intake port 22 and an opposite but preferably lower exhaust port 23; these ports being preferably tapered in a converging relation towards and into their respective cylinder chambers 15 wherein the sleeve valves G are slidable. Suitable oil ducts 24 may be provided in the block B for oiling the piston and sleeve action, in any approved relation.

The cylinder block B is of course mounted on the crank case C in any approved and conventional relation, and the crank shaft C is conventionally connected to the pistons E.

The sleeve valves G are provided in each of the cylinder chambers 15 in snug sliding relation therein and each of these sleeve valves G includes an upper transverse intake port 26 and an opposite but preferably lower exhaust port 27 adapted to cooperate respectively with the ports 22 and 23 of the engine block. The ports 26 and 27 may be of any length circumferentially about the sleeve desired, in order to render the intake and exhaust most efficient. These ports, however, are horizontally elongated as illustrated in Figure 4 of the drawings.

Referring to the novel means H and L for slidable operation of the sleeve valves G, the principle of operation is substantially the same as set forth in my above mentioned co-pending application, but the operating details are different and considered an improvement.

The cam means H includes a cam shaft 30 longitudinally bearing in the crank case C, in any approved manner, and connected by means 31 with the crank shaft D for operation at one-half crank shaft speed and preferably rotatable in the same direction. For each sleeve valve the cam shaft 30 is provided with main and auxiliary cams 32 and 33 respectively, which respectively have throw portions 34 and 35, arranged in a relation of 90° about the cam shaft. The de-

sign of these cams is important as insuring an efficient operation of the sleeve valve for intake and exhaust action. The main cam is so designed that from the throw portion 34 in the direction of rotation of the cam shaft, the same abruptly slopes with a preferably flat side in direction toward the axis of the cam shaft 30, and from thence gradually increases on an arc, the radius of which gradually increases from the axis of the cam shaft 30 until the throw portion 34 is reached. In contradistinction to this the auxiliary cam 33 from its throw portion 35 gradually slopes on an arc at a gradually decreasing radius from the throw portion 35 in a direction of rotation of the cam, and at the approach to the throw portion 35 in the direction of rotation of the cam the auxiliary cam has preferably a flat side and slopes abruptly into the throw portion. The reason for so designing the pair of cams for each sleeve valve is that the distance from one point of one cam to a diametrically opposed point on the other cam should be the same, at any point from which such measurement is taken, and which feature is set forth in my co-pending application above referred to, and is fully explained therein.

Referring to the means L which the cams operate to cause an operation of the sleeve valves G, the same is somewhat of a departure from the construction of my co-pending application above referred to, and includes a crescent shaped frame 38 having a hub portion 39 intermediate its ends provided with a passageway 40 therethrough transverse to the plane of the crescent shaped frame 38, and which passageway is adapted to detachably receive a pin 41 which is supported by spaced bracket arms 42 and 43 integral or rigid with a detachable bracket wall 44 which is formed as part of the crank case C at a side thereof. The crescent shaped frame 38 is thus pivotally supported by the pin 41 in a vertical plane and below the pivot connection of the frame 38 the same provides a forwardly extending half circled supporting arm 45 and above the same is provided a quarter circled arm 46 rigid with the arm 45, although reduced in thickness with respect thereto, the arm 46 being only of one half the thickness of the arm 45, for a purpose which will be subsequently described. The free ends of the arm portions 45 and 46 are spaced at 48, to permit the assemblage of the frame 38 with the cam shaft 30 extending centrally thru the passageway between the arms 45 and 46, as is illustrated in the drawings.

At its free end the lower and longer arm portion 45 is provided with a slot or recess 49 which radially opens outwardly and is adapted to slidably bear on the intermediate portion of a pin 50 which is supported at

its ends by spaced brackets 51; the brackets 51 being secured on the lower end of the sleeve valve G below the cylinder block.

As the cams act upon the frame 38 it is readily obvious that the same is rocked on its pivot pin 41 and due to the loose connection with the pin 50, the sleeve valve G will be reciprocated within its cylinder compartment to cause the proper operation thereof.

10 Referring now to the specific parts of the frame 38 with which the main and auxiliary cams 32 and 33 cooperate, the lower or longer arm 45 midway between the ends thereof is provided with a detachable supporting bolt or member 52, transversely extending beyond the outer side of the frame arm 45, where the same rotatably supports an anti-friction roller 53, which includes inner and outer races with ball bearings therebetween,

15 the outer race of the anti-friction roller 53 being adapted to be engaged at its outer circumference by the periphery of the auxiliary cam 33 during rotation of the latter.

At its free end the reduced shorter arm 46 is provided with a detachable bolt or pin 55, which extends laterally from the reduced side of the shorter segmental arm 46; the said pin or bolt 55 being adapted to pivotally support the one end of a preferably straight arm 57 which extends from the pivot member 55 in a direction away from the cylinder sleeve valve G. This construction is best illustrated in Figure 7 of the drawings. A vertical pin 60 is rigidly supported by the arm 46 adjacent the free end of the movable arm 57, and the movable arm 57 is provided with an aperture 61 therein thru which the pin 60 loosely extends. At its free end the pin 60 is screw threaded for 20 adjustably receiving a retaining nut 62, and upon the pin 60 is a spring 63 under compression, engaging the nut 62 at one end and the free end of the arm 57 at the opposite end, to normally force the free end of the arm 61 towards the pivot pin 41 of the frame 38. Intermediate its ends and preferably closer to the pivot pin 55, the arm 57 is provided with a detachable pin or bolt 65, on which an anti-friction roller 66 25 is detachably supported, which consists of inner and outer faces with ball bearings therebetween, the outer race being adapted to be engaged by the outer periphery of the main cam 32 during rotation of the latter.

30 It is to be noted that the anti-friction rollers 53 and 66 are located at opposite sides of the frame 38, and that they are at diametrically opposed locations with respect to the cam shaft 30, so that the one roller 35 engages the auxiliary cam and the other roller engages the respective main cam; this construction being provided in connection with each sleeve valve operating mechanism.

35 The crank case C is altered slightly in construction beyond the conventional forma-

tion to receive details of the means L, and as above mentioned the bracket plate 44 is detachably connected, as at 68, to the body portion 69 of the crank case in order to pivotally support the frame 38. In the top 70 wall of the crank case C laterally of each cylinder block, is provided a top opening 70 in the crank case top wall thru which the upper ends of the frames 38 extend, and detachable caps 71 are secured in any approved manner over these openings 70, to 75 permit of facile access to details of the operating means L.

As before mentioned a cylinder head M is provided in connection with each cylinder 80 of the engine A. Each cylinder head comprises an outer substantially cylindrical shaped shell 80, which is insertable downwardly into the upper end of the cylinder chamber 15, so that the outer circumference 85 thereof is spaced from the inner surface of the walls of the cylinder chamber 15, to provide an annular compartment 81 which extends longitudinally along the upper portion of the cylinder chamber 15, and into 90 which the upper end of the sleeve valve G extends. The upper margins of the other shell 80 are provided with laterally extending attaching flanges 82, secured over the top surface of the cylinder block B and provided with openings 83 therethrough for receiving attaching bolts 84 by means of which to secure the respective cylinder heads in place on the cylinder block B, as is well illustrated in Figure 5 of the drawings. 100 These flanges 82 are provided with transverse apertures 86 therethrough aligning with the openings 19 thru the top wall of the cylinder block B, and thru which water 105 passes into the compartment 90 of the water receiving hood P.

An inner shell 91 is also provided as part of each cylinder head M, which is of tubular formation and extends centrally upward thru the passageway 92 provided thru the outer shell 80. This inner shell 91 is integral at its lower end with the lower end of the outer shell 80, and from this connection, illustrated at 94 in Figure 1 of the drawings, the inner shell 91 extends upwardly in spaced relation with the inner walls of the outer shell to provide an annular space 95 open at the top of the compartment 90 of the water hood P, so that water may enter and circulate about the space 95 to cool the upper portion of the sleeve valve and reciprocating parts of the sleeve valve operating mechanism, as well as to generally cool the entire upper part of the cylinder in a novel relation.

110 The inner shell 91 is provided with a downwardly facing frusto-conical compartment 98, which is of greatest diameter at its outlet into the chamber within the sleeve valve G and tapers in a converging relation 115

therefrom upwardly to a spark plug supporting wall 99 which is integrally provided in the shell 91 at a location about one-third the distance above the lower edge of said inner shell. This wall 99 is provided with a screw threaded opening 100 therethrough for detachably receiving a spark plug 101, so that the electrodes of the spark plug may depend into the upper reduced end of 10 the tapered compartment 98 of the cylinder head M.

A transverse web portion connects the inner and outer shells 91 and 80 to provide an intake port 105 transversely thru the cylinder head M, which aligns directly with the intake port 22 of the cylinder block B for the respective cylinder in which the cylinder head M is assembled, so that the inflowing fuel charge passes thru the ports 22 and 105 into the upper or smaller end of the tapered compartment 98. It is to be noted that the intake port 105 is relatively long transversely about the cylinder head M and the intake port 105 tapers in a constricted relation towards the center of the compartment 98, as is illustrated by the tapered sides 110 in Figure 6 of the drawings. Also, the web portion connecting the inner and outer shells is downwardly sloped from the bottom 25 of the intake port 105 to provide a downwardly sloping surface 112 from the outer edge of the intake port 105 to the intersection of the surface 112 with the upwardly tapered surface which defines the tapered compartment 98, as is well illustrated in 30 Figures 1, 2 and 14 of the drawings. It is to be noted that the intake port 105 is flush with the lower surface of the wall 99 so that the inflowing charge will pass directly 35 onto the electrodes of the spark plug 101, and be whirled about in a turbulent flow within the tapered compartment 98, due to the manner in which the same enters the compartment 98 and due to the shape of 40 said compartment 98.

The outer shell 80 at a location above the intake port 105 is provided with an annular groove 114 wherein a preferably expansible packing ring 115 is received, which engages 50 in a sealed connection with inner wall of the sliding sleeve valve G, to seal against leak of compression above the intake port 105. Below the intake port 105 the outer shell 80 is also provided with an annular groove 117, wherein an expansible packing or piston ring 118 is adapted to be received, in a sealed engagement with the inner wall of the sleeve valve G, below the intake port 105. This piston ring 118 is formed as best 55 illustrated in Figure 14, with reduced flanges 119 at the top and bottom margins thereof, which engage the exterior surfaces of the outer shell 80 above and below the groove 117, in order to best anchor the packing ring in position to provide the most efficient 60

seal. It is to be noted that the packing ring 118 is considerably wider than the upper packing ring 115, and this is provided because of the vertically offset relation of the intake and exhaust ports of the sleeve 70 valve G, which the piston ring 118 is adapted to seal at different locations in the sliding movement of the sleeve valve.

The inner tubular shell 91 extends at its upper end above the top surfaces of the 75 top wall of the cylinder block B and above the top surface of the flanges 82 of the cylinder heads M. Adjacent to the plane of the top surface of the flanges 82, each cylinder head M on the inner shell 91 thereof is 80 provided with an annular hood supporting flange 120 which provides an upwardly facing shoulder. The upper end of the shell 91 above the flange 120 is externally screw threaded for detachably receiving a hood 85 clamping nut 122.

The water hood P extends the length of the engine A, and the same is provided with side walls 125, which extend along opposite sides of the engine. It is furthermore provided with a top wall 126, and for each cylinder head M the hood top wall 126 is provided with a depending tubular extension 128 which extends downwardly into the compartment 90 of the hood, for freely receiving 90 the upper end of the inner shell 91 of the respective cylinder heads M; the lower edges of each of the tubular portions 128 resting on the supporting flange 120 of the respective cylinder head with which it cooperates, 95 in order to properly support the hood P in position against eccentric clamping action. In this position the lower flanged ends of the side walls 125 rest on the top surface of the top wall of the cylinder block B, and packing 130 is preferably provided between the abutting edges at the bottoms of the side walls 125 and the top wall of the cylinder block B, to provide a liquid seal. In 100 this position the top screw threaded ends of the inner shells 91 extend above the top surface of the top wall 126, for receiving the nuts 122 which are then clamped against the top wall of the hood, to hold the latter in place. Washer arrangements 135 are provided at the location where the tubular shells 91 leave the hood, which the nuts 122 force into engagement with the top wall of the hood about each inner shell 91 to seal the juncture and prevent leakage. The hood D 110 may be provided with any suitable connection 140, illustrated in Figure 3, which may be connected with the water cooling radiator (not shown).

From the foregoing description of this invention it is believed that the operation of the engine will be apparent. In Figure 10 is illustrated the position of the cam for the start of the intake of fuel to the cylinder chamber for this operating mechanism. It 125 130

will be noted that the throw of the main cam 32 is just about to lift the roller 66 on which it operates to the highest extent, and of course this will rock the frame 38 on its 5 pivot pin 41 and lift the sleeve valve G. The position of the sleeve valve and particularly its intake port 26 for this arrangement of the cam (Figure 10) is illustrated in Figure 14, and it is to be noted that the intake 10 port 26 is just about to come into alignment with the aligning ports 22 and 105, and at which instance the suction, due to the downward traveling piston, will cause an intake of the fuel charge into the cylinders of the 15 engine. The fuel charge, due to the compartment 98 in which the same first enters, will first pass in a turbulent flow directly across the electrodes of the spark plug, and most efficiently enter the cylinder chamber 20 within the sleeve valve G, as is readily apparent.

The position of the cams illustrated in Figure 11 shows the relation which they assume when the intake is just starting to close 25 and the main throw portion of the main cam 32 has moved beyond the roller 66 on which it operates, and the throw of the cam 32 is decreasing with respect to the roller 66, whereas the auxiliary cam 33 is operating 30 with a gradually increasing radius on its roller 53, which action lowers the sleeve valve G to bring the port 26 downwardly past the aligning ports 22 and 105. The cams move from their position illustrated in 35 Figure 11 to their position illustrated in Figure 12, and during which movement the compression stroke of the piston is taking effect. The view illustrated in Figure 12 shows the positions which the cams assume 40 when the throw of the crank shaft is at top center, and the start of the power stroke is taking place. During this position the intake and exhaust ports of the sleeve valve are closed to alignment with the housing in 45 take and exhaust ports, as is quite apparent, and during the power stroke the cams move from the position illustrated in Figure 12 to the position illustrated in Figure 13.

In Figure 13 the cams show the position 50 which they assume at the start of the exhaust stroke, and the relation of the exhaust port of the sleeve valve G for this position of the cams is illustrated in Figure 2 of the drawings, for it shows the sleeve valve G lowered to start to align the exhaust port 27 with the exhaust port 23 of the engine block 55 B to permit the escape of exhaust gases.

In so far as the individual cylinder head construction for each cylinder is concerned, 60 it is apparent that the same not only admits of better access to the working parts of the engine, but due to the novel arrangement thereof, the fuel charges inlet so as to maintain the spark plug electrodes clean. The 65 most important feature in the novel con-

struction of the individual cylinder head, is in the fact that by projecting into the upper portion of the cylinder the same provides an annular compartment which slidably receives the upper end of the sleeve valve in 70 such a piston ring sealed relation at opposite sides of the intake port of the housing that the engine is especially desirable for use where high compression is desired. Thus, the engine will operate with increased efficiency with good fuel, and will effectively 75 operate under circumstances where low grade fuels are used, due to the absence of loss of compression.

Various changes in the shape, size, and arrangement of parts may be made to the forms of invention herein shown and described, without departing from the spirit of the inventions or the scope of the claims.

I claim:

1. In an internal combustion engine the combination of a cylinder having port means therein, a sleeve valve slidable in the cylinder having port means therein adapted to cooperate with the cylinder port means, piston means slidable in the sleeve valve, a segmental pivotally connected frame having a pivotal slidable connection with the sleeve valve, cam shafts, and cam means on the cam shafts for operating on said pivoted frame 95 to cause a reciprocatory movement of said sleeve valve.

2. In an internal combustion engine the combination of a cylinder having port means therein, a sleeve valve slidable in the cylinder having port means therein adapted for cooperation with the cylinder port means, piston means slidable in the sleeve valve, a crescent shaped frame pivoted intermediate its ends, means providing a slidable pivot connection of the crescent shaped frame at one end with said sleeve valve, a cam shaft extending thru the hollow of the crescent shaped frame, a pair of cams on said cam shaft having the throws thereof relatively offset circumferentially about the cam shaft, and anti-friction rollers carried by the crescent shaped frame at diametrically opposed locations on the crescent shaped frame, one of said anti-friction rollers having engagement with one of the cams and other roller having engagement with the other cam.

3. In an internal combustion engine the combination of a cylinder having port means therein, a sleeve valve slidable in the cylinder having port means therein adapted for cooperation with the cylinder port means, piston means slidable in the sleeve valve, a crescent shaped frame pivoted intermediate its ends, means providing a slidable pivot connection of the crescent shaped frame at one end with said sleeve valve, a cam shaft extending thru the hollow of the crescent shaped frame, a pair of cams on said cam shaft having the throws thereof relatively 120

they should have a value approximating that given by Equation 3 above. The washers 59 which seal the carbon chamber also act as a series elasticity 95 to furnish a force which holds the hats 61 in engagement with the needle arm 65. This elasticity 95 should be made small in order not to reduce the low frequency output of the reproducer.

By comparison of Figs. 3 and 4 it will be seen that Fig. 4 departs from the ideal case in having part of the shunt elasticity in series with the conductance and part in shunt instead of all in shunt, as shown in Fig. 3. Since Equation 5 above holds only when all of the elasticity is in shunt to the conductance, the ratio of the elasticity 77 to the elasticity 79 should be made as large as possible and therefore insure that the network more nearly approximates the condition covered by Equation 5.

Electrical networks such as that shown in Fig. 1, for example, may be terminated at each end in a variety of ways, the impedance of the arrangement depending upon the manner of its termination. Two common terminations are the mid-series type and the mid-shunt type. In the mid-series type, the end series inductances have values equal to one-half of the value of the inductance for a full section and in the mid-shunt termination, the capacity has a value one half the capacity of that of a full section. The mechanical arrangement of Fig. 9 may be made to have a mid-shunt termination, for example, at the needle end by having the elasticity 71 twice the elasticity of the full section, that is, elasticity 71 would have a value twice the elasticity of element 74 or 77, in those cases in which the elasticity 73 may be disregarded. In other cases the elasticity 71 should have a value only approximately one half of that of the elements 77 so as to give the terminating section the same impedance as the other sections. The termination at the carbon chamber end need not be made special, since the impedance of the carbon chamber represents the impedance of an infinite number of sections. A ready explanation of the manner in which the network should be terminated is shown in Fig. 2, where both the series and the shunt elements are split into two parts. The inductance of a full section comprises the sum of elements 81 and 82, while the total capacity for a single section comprises the sum of the capacities 83 and 84. If the network is terminated at the points 86, the inductance 81 is mated with the capacity 85 which is the same value as either capacity 83 or 84. Inductance 82 is mated with capacity 83. Inductance 87 is mated with capacity 84 and inductance 88 is mated with capacity 89, all of the inductances shown being of equal value and all of the capacities shown being of equal value.

Such a filter can also be terminated at the points 90 and 91, inductance 81 and capacity 85 being omitted, or the network can be terminated at the points 92 and 93, inductances 81 and 82 and capacities 85 and 83 being omitted.

It is to be understood that this invention is not limited to the particular forms that have been described in detail above, since they may be variously modified without departing in any wise from the spirit of the invention as defined in the appended claims.

The invention claimed is:

1. A phonograph reproducer, comprising a carbon button, a flexible closure therefor, a lever arm arranged to be vibrated in accordance with speech frequency vibrations occurring on a sound record, a mechanical transmission line between said lever and said closure comprising a plurality of spaced weights separated by a loose packing of air-cushioned material, said carbon chamber being of sufficient depth to avoid appreciable reflection losses from the wall of said chamber opposite said closure back to said closure.

2. An electric device comprising electrodes, conductive granular material packed between said electrodes, means comprising a flexible member contacting with said material for subjecting said material to mechanical vibrations, and means cooperating with said granular material for causing said granular material to work into a mechanical impedance on that side of said material opposite said flexible member having an impedance of the same order of magnitude as the impedance of said means which subjects said material to mechanical vibrations.

3. An electric device comprising electrodes, a chamber substantially filled with carbon granular material, means for causing an electric current to flow through said granular material, and a flexible member included as one side of said chamber, said chamber being of sufficient depth that the carbon material adjacent the back wall of said chamber is substantially unaffected by the mechanical vibrations of said flexible member.

4. An electric device comprising a chamber substantially filled with carbon granular material, a flexible member acting as one side of said chamber, means for impressing mechanical vibrations of signaling frequencies upon said member, means for supplying an electric current to a portion of said granular material, the mass of said carbon in said chamber being of sufficient depth and cross section as to cause the active carbon material to work into an impedance of the same order of magnitude as the impedance of the said means for impressing mechanical vibrations upon said granular material.

sleeve valve of an internal combustion engine comprising a substantially crescent-shaped frame having the ends thereof spaced from each other, means between the 5 ends on said frame for pivotally mounting the frame, a roller rotatably mounted on the frame between said last mentioned means and one of the ends of the frame, a lever pivoted at the other free end of the frame,

a cam engaging roller rotatably mounted on 10 said lever eccentrically of the pivot mounting of the lever, and spring means associated with the frame and the lever for urging the latter in a direction to move the last mentioned roller towards the first mentioned 15 roller.

LUTHER A. GAW.
